PATTERN AND GUIDE STRIP

Richard S. Knight, New York, N. Y., assignor to
 Lockstrip Manufacturing Corporation, Long Is-
 land City, N. Y., a corporation of New York

Application April 18, 1940, Serial No. 330,272

2 Claims. (Cl. 94—17)

This invention relates to pattern and guide strips used in connection with the laying of terrazzo and like floors. Pattern and guide strips have been used for many years in the laying of terrazzo and like floors in which the pattern and guide strip becomes a physical part of the floor defining the individual panels or sections of the floor and also becoming an integral part of the pattern, design or configuration in which the floor is laid out to give a pleasing appearance. Such pattern and guide strips, when laid, although they are intended to define the edges of the several panels or sections making up a terrazzo floor and to sharply define the edge of the pattern, design or configuration in which the floor is laid out, at times break away from the panel or section with which they are originally associated and take a wavy or sinuous configuration in the floor, often opening up along the edge of the terrazzo. Such objectionable relation between the panel or section of terrazzo and the strip results apparently from a number of factors, such as shrinkage of the terrazzo in the underbed from the strip, and settlement of the building or floor.

This invention overcomes such difficulties and provides a strip, when used in a floor, which when laid according to this invention, remains an integral part of the panel or section of terrazzo with which it is originally associated, maintaining the exact line along which the strip is initially laid, defining the edge of the pattern, design or configuration as predetermined when the floor is laid, providing a bond between the underbed and the terrazzo in their relation to the strip itself, providing means for indicating the depth to which the lower portion of the strip is to be inserted in the underbed and a measure for the depth of the terrazzo finish.

In the drawings, Fig. 1 is a top plan view of part of a floor showing simple designs, having a pattern and guide strip embodying this invention; Fig. 2 is a perspective view of the strip; Fig. 3 is a section on the line 3—3 of Fig. 1; Fig. 4 is a side elevation of the strip; Fig. 5 is a top plan view thereof; Fig. 6 shows a modification of the type of strip shown in Fig. 2; Fig. 7 is a side elevation of the strip of Fig. 6; Fig. 8 is a top plan view thereof; Fig. 9 is a section on the line 9—9 of Fig. 7; Fig. 10 is a section on the line 10—10 of Fig. 9, with the strip embedded in a finished floor.

The terrazzo floor 1 consists of a cementitious underbed 2 carried usually on a concrete foundation 3 and provided with a superposed terrazzo

finish or layer 4, the underbed 2 and the terrazzo surface having associated therewith a pattern and guide strip 5. The pattern and guide strip is made of suitable thin metal, such for instance as brass, in suitable lengths, for instance six feet, and approximately seven-eighths of an inch deep, inherently flexible and capable of being bowed, sprung and bent into various configurations to conform to predetermined designs. An outwardly extending member 6 in the form of a wing is punched on three sides from the body of the strip and is bent outwardly at an angle to the face of the strip, remaining attached to the strip along its upper edge and forming an opening 11 in the face of the strip. The outwardly extending member is provided with a punched out opening 7 and preferably with two notches 8 extending inwardly on both side edges of the member 6. The member 6 between the opening 7 and the face of the strip is provided with an anchoring member 9 in the form of an upwardly extending lip rising about one-sixteenth of an inch from the plane of the member 6. The outwardly extending members 6 are formed on 25 one side only of the strip, about every six inches along the face of the strip. Elongated openings 10 may also be formed in the strip if they are found desirable.

In laying a floor, the underbed 2 is first laid and 30 when this bed has partially set but is still plastic the pattern and guide strips 5 are forced into the underbed to a depth at which the members 6 lie intimately in contact with the top of the underbed 2. These strips are laid according to 35 a predetermined pattern, either plain or highly fanciful, it being understood that the strips being flexible may be laid in the form of an endless number of designs or patterns. In the course of laying the strip the plastic underbed 2 will flow 40 into the openings 11, and incidentally into the openings 10 if they are present, and anchor the strip in the underbed. The underbed is then allowed to harden or set and the terrazzo layer 4, consisting usually of small chips of suitable 45 marble, stones or the like mixed with cement, is laid between the strips which outline each pattern, design or configuration. The terrazzo mixture flows into the openings 7 and the notches 8, contacting and bonding with the surface of the 50 underbed 2, thereby uniting the terrazzo layer with the surface of the underbed 2. The terrazzo layer also flows entirely around the anchoring member 9, the entire mass of terrazzo layer 4 extending from the top surface of the underbed 55 2 to the top edge 12 of the strip 5. The terrazzo

is worked downwardly by rolling or other suitable operations to compact the same and eliminate air spaces and other objectionable features. The terrazzo, when it has hardened, is then ground, to provide a smooth, finished surface to the floor, which grinding operation often involves the grinding of the top edge 12 of the strip. The thickness of the terrazzo is determined by the distance from the top surface of the member 6 to the top edge 12 of the strip. As heretofore stated, the members 6 extend outwardly all on the same side of the strip. When the strips are laid with respect to each pattern, design or configuration, they are so laid that the members 6 extend inwardly with respect to the particular panel, design or configuration with which the strip is to form the outline. Care is taken by the workmen to so arrange the strips that for each pattern, design or configuration the members 6 extend inwardly, and inasmuch as a strip outlining one side also separates or defines a side of an adjoining panel, the adjoining panel will have members 6 extending inwardly on three sides only if the pattern is a four-sided figure. In other words, a strip common to two adjoining panels has members 6 extending into one panel but not into the other panel with which it is associated.

It will be evident that the underbeds for adjoining panels are united together through the openings 11 (and 10, if the same are present) and that the terrazzo is bonded by a plug or neck 13 of the terrazzomaterial which extends substantially vertically through the openings 7. The terrazzo also engages against the anchoring member 9 in its lateral course from one anchoring member 9 to the anchoring members on both sides thereof. The extent of the plug or neck 13 into the opening 7 to its bond with the underbed, and the engagement of the lateral run of the terrazzo with the anchoring members 9, is slight in depth at the actual surfaces of engagement (equal to the thinness of the metal of the members 6 or the height of the anchoring member 9) but, nevertheless, this engagement is sufficient to secure a complete and continuous attachment, from member 6 to member 6, of the entire strip, to the terrazzo layer, even though the thickness of the metal forming the members 6 and the height of the anchoring member 9 is as little as two thirty-seconds of an inch. In fact, it is advisable that the presence of metal in the terrazzo layer be kept to a minimum, in order that the terrazzo layer should not be thinned out and make it subject to fracture or chipping.

It will be evident from the foregoing description that the anchorage of the strip in the underbed 2 is firmly established through the openings 11, ensuring the strip against upward movement, and that each individual panel or section of terrazzo is completely isolated, as far as direct physical attachment is concerned, from each adjoining panel or section and that the portion of the strip above the underbed 2 is anchored by the members 6 and 9 to the under surface of the terrazzo layer, the amount of penetration of

these members into the under surface of the terrazzo layer being slight but, nevertheless, sufficient to compel each strip in its full length to lie closely against the edge of the panel or section 5 to which it is anchored and retain the position in which it is laid as its panel or section shrinks or settles.

A modification of this invention is shown in Figs. 6 to 10, in which the anchoring member 9 10 takes the form of two grooves or depressions 14, stamped into the top face of the member 6, said grooves extending from the corners of the members 6 diagonally inwardly and terminating at the outer edges of the openings 7. The terrazzo, 15 when it is laid, will enter said grooves or depressions 14 and form extensions on the underside of the bed integral with the plug 13 which is formed in the opening 7.

I claim:

20 1. In a terrazzo or like flooring having an underbed and a top layer, a pattern and guide strip comprising a thin, inherently flexible strip of material to provide a pattern for a terrazzo floor design, a plurality of members extending outwardly from the body of the strip and all extending on the same side thereof with the lower edge of the strip secured in the underbed, openings 25 in the body of the strip beneath said members, portions of the underbed being within the openings in the body of the strip, openings extending through said members, portions of the top layer extending through said openings and bonded to the surface of the underbed, the portions of the members bordering said openings 30 contacting said top layer on the lower surface thereof and anchoring the upper portion of the strip to said top layer, said members being provided with a lip extending upwardly from the plane of the members and the under portion of 35 the top layer being in engagement with said lip and the lip extending upwardly into the under surface of the top layer.

2. In a terrazzo or like flooring having an underbed and a top layer, a pattern and guide strip 45 comprising a thin, inherently flexible strip of material to provide a pattern for a terrazzo floor design, a plurality of members extending outwardly from the body of the strip and all extending on the same side thereof with the lower edge of the strip secured in the underbed, openings 50 in the body of the strip beneath said members, portions of the underbed being within the openings in the body of the strip, openings extending through said members, portions of the top layer extending through said openings and bonded to the surface of the underbed, the portions of the members bordering said openings 55 contacting said top layer on the lower surface thereof and anchoring the upper portion of the strip to said top layer, said members being provided with downwardly extending grooves, portions of the under surface of the top layer extending into said grooves, said top layer and said grooves thereby being anchored together.

RICHARD S. KNIGHT.
